UNITED STATES PATENT OFFICE.

WALTER C. DELZELL, OF LOS ANGELES, CALIFORNIA.

BLADE-GRINDING DEVICE.

Application filed July 11, 1921. Serial No. 463,924.

To all whom it may concern:

Be it known that I, WALTER C. DELZELL, a citizen of the United States, residing at Los Angeles, in the county of Los Angeles and 5 State of California, have invented certain new and useful Improvements in Blade-Grinding Devices; and I do declare the following to be a full, clear, and exact description of the invention, such as will enable 10 others skilled in the art to which it appertains to make and use the same.

My invention relates to improvements in blade sharpening devices and more particularly to those employing a roller provided 15 with a helical grinding surface, two rollers of this character being usually disposed side by side so that the grinding ribs of one roller are received between the ribs of the other roller.

20 The object of the present invention is to provide novel means whereby the grinding ribs may be moulded in retaining grooves in the rollers and effectively keyed therein.

With the foregoing in view, the invention 25 resides in the novel features hereinafter described and claimed, the descriptive matter being supplemented by the accompanying drawings.

Figure 1 is a top plan view showing two 30 rollers constructed in accordance with my invention mounted in a conventional frame.

Figure 2 is a horizontal sectional view.

Figure 3 is a vertical transverse sectional view as indicated by line 3-3 of Fig. 1.

Figure 4 is an elevation of one of the 35 rollers before the grinding rib is moulded.

Figure 5 is a longitudinal sectional view as indicated by line 5-5 of Fig. 6.

Figure 6 is a transverse sectional view as 40 indicated by line 6-6 of Fig. 4.

Figure 7 is an elevation showing a different form of construction.

In the drawings above briefly described, I have illustrated two of the improved rollers 45 operatively associated with each other, but since the construction of both rollers is the same, only one will be described. The numeral 1 designates a roller formed of wood or any other appropriate material and here 50 shown mounted on a mandrel 2 having trunnions 3 rotatably supported by any appropriate form of frame 4. The periphery of the roller 1 is formed with one or more grooves 5 which preferably extend helically 55 as shown. At circumferentially spaced

points, the grooves 5 are intersected by openings 6 which are drilled longitudinally through the roller and may either extend from end to end of the latter as seen in Figs. 1 to 6, or may extend inwardly from both 60 ends as illustrated in Fig. 7. The openings 6 are by preference so located that they extend across the bottoms of the grooves 5 and form grooves 6a.

A plastic abrasive material 7 is moulded 65 in the grooves 5 and extends beyond the periphery of the roller to form a helical grinding rib. When this material is moulded in the grooves, it runs into the openings 6 and thereby forms keys 8 integral with the grinding ribs, said keys serving to effectively secure the ribs in the grooves 5 and acting also to prevent any possible circumferential creeping of the ribs in the grooves. As indicated in Fig. 2, the keys 8 of adjacent groove 75 portions will integrally join each other in some instances, while in others, the keys will extend an insufficient distance from the ribs to permit their uniting. In either case, the desired results are obtained. 80

After the moulding operation has been completed and the plastic abrasive has set sufficiently, the ribs are smoothed and trued in any suitable way.

While one of the rollers might be advantageous for certain uses, I prefer to associate two of them in the manner shown in the drawings, the ribs of one roller being received between the ribs of the other. Thus, when one roller is rotated by means of a 85 crank or the like 9, it will turn the other roller, as if the two were geared together. When the association of rollers herein shown is employed, a sharp edge may be quickly placed on a knife or other blade by properly 90 rotating the rollers and holding the blade in the angle between them. It is not necessary to longitudinally shift the blade since the grinding ribs extend helically and thus each 95 rib acts on said blade from one end to the 100 other.

From the foregoing taken in connection with the accompanying drawings, it will be seen that I have produced a novel device for carrying out the objects of the invention in 105 an expeditious manner. The details disclosed are preferably followed but within the scope of the invention as claimed, numerous minor changes may of course be made.

I claim:

1. A grinding device comprising a roller having a peripheral channel and circumferentially spaced openings communicating with said channel and extending across the bottom of the latter in the form of transverse grooves, and an abrasive plastic moulded in said channel and grooves and having integral laterally extending keys moulded in said openings.
2. A grinding device comprising a roller having in its periphery a helical groove, said roller having circumferentially spaced openings each communicating with a plurality of convolutions of said groove, and an abrasive

plastic moulded in said groove and having integral keys moulded in said openings.

3. A grinding device comprising a roller peripherally grooved and having spaced groove portions extending around its periphery, said roller also having circumferentially spaced openings drilled parallel with its axis and intersecting said grooves, and an abrasive plastic moulded in said groove portions and having integral keys moulded in said openings.

In testimony whereof I have hereunto set my hand.

WALTER C. DELZELL.
